SYMMETRICAL POLYHEDRAL INTERLOCKING PUZZLE

Stewart T. Coffin, Old Sudbury Road,
Lincoln, Mass. 01773

Filed Feb. 28, 1972, Ser. No. 230,197

Term of patent 14 years

Int. Cl. D21—01
U.S. Cl. D34—15 M

The figure is a perspective view of a symmetrical polyhedral interlocking puzzle, showing my new design.

The design has cubic symmetry, so that the views from all six sides are identical.

I claim:

The ornamental design for a symmetrical polyhedral interlocking puzzle, as shown.
